Patented June 20, 1922.

INVENTOR:
EUGENE CERIAT,
BY: Otto D. Kueger,
his Atty.

UNITED STATES PATENT OFFICE.

EUGENE CERIAT, OF LOS ANGELES, CALIFORNIA.

TILE CONSTRUCTION.

1,420,020.

Specification of Letters Patent. Patented June 20, 1922.

Application filed August 2, 1921. Serial No. 489,213.

To all whom it may concern:

Be it known that I, EUGENE CERIAT, a citizen of the United States, residing at Los Angeles, in the county of Los Angeles and State of California, have invented a new and useful Tile Construction, of which the following is a specification.

This invention relates to devices used in building up walls.

10 One of the objects of this invention is to provide a block or tile that can be built up to form a rigid wall in which the inner face is insulated from the outer face or portion.

15 Another object is to provide L-shaped tiles, to be arranged in a wall so that the longer shank forms the inner and outer surface of the wall while the shorter shank forms the interengaging portion between the 20 inner and outer surface.

Another object is to provide L-shaped tiles, to be arranged in a wall as set forth above, having recesses and ducts in which re-enforcing rods can be arranged for binding the several tiles in each layer and for 25 binding the several layers of tiles one layer with the other.

Another object is to provide L-shaped tiles of this type of a shape and form to 30 allow a ventilation in a vertical and horizontal direction when the tiles are placed in a wall.

Other objects will appear from the following description and appended claims as 35 well as from the accompanying drawing, in which—

Fig. 1 is a perspective view of a typical unit in form of a block, molded or finished in itself before being placed in a wall.

40 Fig. 2 is a top plan view of a wall section, illustrating the interengaging of several blocks.

Each single block or unit is made with the idea in view of facilitating and simplifying the building up of a wall. The preferred form, illustrated in Fig. 1 in detail, is of L-shape, the longer shank 3 forming normally the inner and outer surface of a wall, while the shorter shank 4 forms an 45 intermediate member or portion between the inner and outer surfaces of a wall when the block is so placed. All the edges 5, 6, 7 and 50 8 of the longer shank portion 3 are preferably provided with grooves, as indicated at

9, so that the wall, inside as well as outside, can be fully and well sealed or grouted in, as indicated at 10 in Fig. 2. The edges 11 and 12 are also preferably provided with grooves, as indicated at 13. The shorter shank-portion 4 is furthermore provided with a passage 14 to allow the insertion of vertical re-enforcing rods. The end of the shorter shank 4 is preferably cut out as indicated at 15, leaving the proportionally small terminations 16, for purposes which 60 will be described more fully hereafter.

In building up a wall, as illustrated in Fig. 2, the ends 17 of the longer shank-portions of the several blocks are placed against the shoulders 18 of the joining 70 blocks so as to bring the surface 19 of one block flush with the surface 19 of the adjoining block. The re-enforcing rods 20 and 21 are placed in the grooves 9, so as to become embedded between the several 75 layers of blocks in a wall.

To assure a well aligned wall, the longer shank-portions 3 are disposed in a wall properly spaced so that the ends 16 of the shorter shanks 4 do not come into contact 80 with the inner surface of the longer shank-portions. In making blocks or tiles of this type, it is impossible to avoid slight differences in the length of the shank portions, and, if the blocks or tiles were placed so 85 close as to touch one another, it would normally be hard to align the outer surfaces of the many blocks in a wall. Under the arrangement, described above, the slight space, indicated at 22, may differ between 90 different blocks without bringing the outer surfaces of the several blocks out of alignment. The cut-outs 15 in the ends of the shorter shank-portions serve to form horizontal ventilating passages, as indicated 95 at 23.

Re-enforcing rods 24 are disposed in the passages 14 of the blocks, being grouted in, as indicated at 25, serving to interconnect the several layers in a wall and re-enforcing 100 the whole wall.

The different layers in a wall are, of course arranged so as to bring the several blocks in one layer suitably shifted over the blocks in the layer above or below, as indicated in 105 dotted lines at 26.

The spaces between the shorter shank-portions 4 and the longer shank-portions 3 serve

as passages for vertical ventilation within the wall, intercommunicating with the horizontal ventilation passages.

Having thus described my invention, I claim:

1. In a tile structure, units having L-shaped cross-section, the longer of the shanks forming the outer and inner surface of the structure, the shorter of the shanks forming 10 the engaging members between the surfaces, the longer shanks having means to engage for forming flush outside surfaces, the shorter shanks having cut-out portions to form horizontal passages in each of the layers of the structure, the shorter shanks being also disposed in spaced relation to one another to form vertical passages for ventilation, re-enforcing rods embedded between the several layers in the structure, and other 15 20 re-enforcing rods disposed through the shorter shanks for connecting and re-enforcing the structure vertically.

2. In a tile, a rectangular portion to form the face member in a wall, a second rectangular portion projecting at practically right angles from one of the edges of the first-named portion to form the connecting member within the wall for the face members

when face members are disposed in the opposite surfaces of the wall, the second-named portion having means for forming horizontal passages between the inner and outer surfaces in a wall.

3. In a tile, a rectangular portion to form a face member of a wall, a second rectangular portion projecting at practically right angles from one of the edges of one of the flat surfaces of the first-named portion, the free end of the second-named portion having a cut-out to form a horizontal ventilating passage 35 when placed against a second tile, the second-named portion being furthermore provided with a passage from edge to edge practically parallel to the flat faces of the first-named portion for allowing a grouting-in of re-enforcing rods in a vertical direction, the edges of both rectangular portions having grooves 40 45 to allow a grouting-in of adjoining tiles.

In testimony that I claim the foregoing as my invention I have signed my name in the presence of two subscribing witnesses.

EUGENE CERIAT.
